US0D1011040S

(12) **United States Design Patent** (10) **Patent No.:** **US D1,011,040 S**
(45) **Date of Patent:** **** Jan. 16, 2024**

(54) **STORAGE BOX**

(71) Applicant: **Zengfu Huang**, Fujian (CN)

(72) Inventor: **Zengfu Huang**, Fujian (CN)

(**) Term: **15 Years**

(21) Appl. No.: **29/904,847**

(22) Filed: **Oct. 12, 2023**

(51) LOC (14) Cl. **03-01**

(52) U.S. Cl. **D3/297**
USPC ....

Primary Examiner — Steven J Czyz

(57) **CLAIM**

The ornamental design for a storage box, as shown and described.

DESCRIPTION

FIG. 1 is a front, right, and top perspective view of a storage box, showing my new design;
FIG. 2 is a rear, left, and bottom perspective view thereof;
FIG. 3 is a front elevational view thereof;
FIG. 4 is a rear elevational view thereof;
FIG. 5 is a left elevational view thereof;
FIG. 6 is a right elevational view thereof;
FIG. 7 is a top plan view thereof;
FIG. 8 is a bottom plan view thereof;
FIG. 9 is a top perspective view thereof when it is opened; and,
FIG. 10 is a bottom perspective view thereof when it is opened.
The broken lines in the figures depict portions of the storage box that form no part of the claimed design.

1 Claim, 10 Drawing Sheets
